UNITED STATES PATENT OFFICE

163,884

PORTABLE LOADER

Vernon G. Mandt, Columbus, Ohio, assignor to
Mandt Manufacturing Company, Columbus,
Ohio, a corporation of Ohio

Application March 9, 1950, Serial No. 8,420

Term of patent 14 years

(Cl. D14—3)

To all whom it may concern:

Be it known that I, Vernon G. Mandt, a citizen of the United States of America, residing at Columbus, county of Franklin, State of Ohio, have invented a new, original, and ornamental Design for a Portable Loader, of which the following is a specification, reference being had to the accompanying drawings, forming a part hereof.

Fig. 1 is a perspective view of the front and right side of the portable loader, showing the boom in lowermost position;

Fig. 2 is a front view of the portable loader with the boom shown in the lowermost position;

Fig. 3 is a front view of the portable loader showing the boom in a raised position and swung to a position to the left substantially 90° from that shown in Figs. 1 and 2; and

Fig. 4 is a fragmentary top plan view of the portable loader.

The characteristic features of my design reside in the portion shown by means of full lines in the drawings.

I claim:

The ornamental design for a portable loader, as shown and described.

VERNON G. MANDT.
